UNITED STATES PATENT OFFICE.

JAMES F. PATTON AND JOHN E. McALLISTER, OF CLEVELAND, OHIO.

IRONING MACHINE.

Application filed June 2, 1921. Serial No. 474,502.

To all whom it may concern:

Be it known that we, JAMES F. PATTON and JOHN E. McALLISTER, both citizens of the United States, residing at Cleveland, in the State of Ohio, have invented certain new and useful Improvements in Ironing Machines, of which the following is a specification.

The invention relates particularly to that class of ironing machines which include a heated curved metallic shoe which co-operates with a rotating cylinder. In such a machine the roll is generally covered with a soft layer of felt or other similar material over which may be placed a sheet of cloth. It is customary in such machines to provide mechanism for forcing together the shoe and roll and for separating them. A motor or other suitable mechanism is provided for rotating the roll and in some cases mechanism is provided for freeing the roll from the motor so that the roll may be stopped from rotation without stopping the motor. In order to work satisfactorily it has been found necessary or desirable to insert a spring in the mechanism which holds the shoe and roll together in such a way that it will be capable of allowing some relief when materials of varying thickness are passed between the roll and shoe in the process of ironing. Associated with the roll and shoe is generally a feeding table from which the clothes to be ironed may be fed to the roll. In the preferred form of the present invention this table is normally horizontal and admits of a very slight tilting motion under pressure. The arrangement may be such that the tilting movement may effect a separation of the roll and shoe.

In the accompanying drawings is shown an embodiment of the invention. Figure 1 is an end elevation of the ironing machine. Fig. 2 is a longitudinal horizontal section through the shoe. Fig. 3 is a plan view of a portion of the machine showing the mechanism for operating a clutch which controls the rotation of the roll. Fig. 4 is an end view of the fragment shown in Fig. 3. Fig. 5 is a partial front elevation of the machine. Fig. 6 is a horizontal transverse section of a part of the fragment shown in Fig. 5.

The shoe 1 is stationary and the roll 2 is moved toward or from it. The bearing 22 for the roll 2 has projecting from it a lug 3 which is exteriorally threaded to receive

a coil spring 4. The lug 3 has an interior cavity to receive the end of an eye bolt 5, on which is threaded a plug 6 upon the outer surface of which may be screwed the other end of the spring 4. The frame 7 of the machine has a pin 8 below the eye bolt 5. Mounted on the pin 8 is a lever arm 9 pivoted at its upper end to the eye bolt 5. Another pin 10 on the forward end of the frame 7 carries a pivotal segment 11, a projection from which is pivoted at 12 to a link 13 the other end of which engages the eye bolt 5 and the lever arm 9. From the forward end of the arc 11 depends an operating rod 14 which may be operated by any well known means such as the usual pedal (not shown). It will be seen that a downward pull on the rod 14 will cause the eye bolt 5 to contract the spring 4 and force the roll 2 against the shoe 1. The pin 12 never rises to the height of the two opposite pivots 5 and 10 of the toggle so that the toggle will not stay extended to hold the roll and shoe in contact. The movement of the toggle causes the pivot pin 12 to rise. The pivot pin 12 extends outwardly from the arc into position to be engaged when in its uppermost position by a depending hook 15 pivoted at 16 on the frame 7. The hook 15 has a forwardly extending arm 17 in which is set an adjustable set screw 18. The usual feeding board 19 for the ironing machine is pivoted about 16 and is supported by a spring 20 in a substantially horizontal position. In this position the feeding board is in contact with the set screw 18 and a slight pressure on the forward part of the feeding board will compress the spring 20 and depress the arm 17 and so cause the hook 15 to release the pin 12 and allow the roll and shoe to separate. A projection 21 on the hook 15 keeps the pin 12 from rising to the dead center of the toggle so that when released by the hook the pin 12 will fall and the roll and shoe will be separated. This apparatus may be at one end of the machine only or at both ends.

In Figs. 3, 4 and 5 are shown the arrangement provided at the right hand end of the machine for rotating the roll. This apparatus may be duplicated at the left hand of the roll or might be there alone. Mounted in the frame 7 is the shaft 34 on which the roll 2 is rigidly mounted. A clutch member 35 having a key way sliding on a key 54 on the shaft 34 has a collar 36 by which it may

be shifted longitudinally on the shaft 34. Carrying a co-operating clutch is a gear 37 loose on the shaft 34. The gear 37 engages a pinion 38 carried by a worm wheel 39 which engages a worm 40 suitably supported on the frame 7. Adjacent the shaft 34 is a lug 44 in the frame carrying a pin 45 to which is fastened one end of a coil spring 46. The other end of the coil spring 46 engages a lever 49 pivoted on the pin 45. One end 47 of the lever 49 engages the collar 36 of the clutch member 35 and the other end 48 of the lever 49 normally engages a lug 51 carried by the frame. As the roll approaches the shoe the clutch is released to cause the roll to rotate.

A motor 43 is mounted in the lower part of the frame and carries a belt 42 extending upwardly to the pulley 41 on the drive shaft 20 40 of the worm. The motor is provided with two pulleys 62 and 63 on its shaft to provide for different speeds of operation. In order to keep the belt 61 always taut it is arranged so that the weight of the motor is supported by the belt. The base of the motor is provided with a beveled insulating block 64 which will slide in the vertical dovetailed guide 65.

In Fig. 2 is shown a preferred form of device for heating the shoe 1. A gas controlling valve 66 is shown at one end of the machine leading to a mixer 67 from which the pipe 68 leads to about the middle of the

length of the shoe. From the pipe 68 extends in each direction a burner 69. The two burners 69 cover substantially the whole length of the shoe and since the fuel is led into the center of the device a substantially uniform heat throughout the length of the shoe is produced.

We claim as our invention:

1. In an ironing machine, a heated shoe, a roll, a toggle to force the roll and shoe into resilient contact, and independent means to limit the movement of the toggle and hold it in position to keep the roll and shoe in contact.

2. In an ironing machine, a heated shoe, a roll, a toggle to force the roll and shoe into resilient contact, means to grasp the toggle and hold it in position to keep the roll and shoe in contact, and means adjacent the roll to release the grasping means.

3. In an ironing machine, a heated shoe, a toggle to force the roll and shoe into resilient contact, a toggle latch, a feeding board, and means controlled by the feeding board to actuate said toggle latch.

4. In an ironing machine, a roll, a shoe, means to force the roll and shoe into resilient contact including a pin, a hook to hold the pin, and pivoted spring supported means adjacent the roll to release the hook.

JAS. F. PATTON.
JOHN E. McALLISTER.
